UNITED STATES PATENT OFFICE.

RICHARD W. GALLAGHER, OF NEW YORK, N. Y., ASSIGNOR, BY MESNE ASSIGNMENTS,
TO F. BIANCHI TOMPKINS, OF NEW YORK, N. Y.

CARBURETER.

1,163,749.

Specification of Letters Patent. Patented Dec. 14, 1915.

Application filed April 27, 1912, Serial No. 693,717. Renewed September 1, 1915. Serial No. 48,521.

To all whom it may concern:

Be it known that I, RICHARD W. GALLAGHER, a citizen of the United States, residing in the borough of Manhattan of the 5 city of New York, in the county of New York, in the State of New York, have invented certain new and useful Improvements in Carbureters, of which the following is a specification, reference being had to 10 the accompanying drawings, which form a part hereof.

This invention relates to carbureters of the general character and construction of that shown in Letters Patent of the United 15 States No. 976,258, dated November 22, 1910.

The object of the invention is to improve both the construction and the operation of carbureters of the type shown in said Letters Patent.

20 One object of the invention is to provide means whereby the suction by which the mixture is transferred from the mixing chamber to the engine shall be varied with the variation of the supply of gasoline and 25 with the variation of the main air supply, while independent adjustment of the suction, of the gasoline supply and of the air supply is also permitted. In this way it becomes possible to adjust the suction, the 30 gasoline supply and the air supply to the requirements of the engine with which the carbureter is employed and thereafter to vary the supply of the mixture, at the will of the operator, according to the varying 35 load which is put upon the engine.

Another object is to reduce the number of parts which enter into the construction of the carbureter and to make the structure as a whole more compact so that the cost 40 of manufacture is reduced and the liability to breakage and leakage is reduced.

Still another object is to enable the devices whereby the supply of gasoline is varied in proportion to the variation in the 45 supply of air to be placed within the casing of the carbureter, so that such devices are protected from injury and from dust and dirt, while manual adjustment of such devices can be effected readily from the outside of the casing.

Further objects of the invention are to improve the details of construction and operation as will be pointed out more fully hereinafter.

55 The invention will be more particularly

described with reference to the accompanying drawings in which it is illustrated as embodied in a convenient and practical form and in which—

Figure 1 is a view of the improved carbureter partly in side elevation and partly in longitudinal, central section. Fig. 2 is a top view of the same partly in horizontal section. Fig. 3 is a view in transverse section on the plane indicated by the line 3—3 of Fig. 1, looking in the direction of the arrows. Fig. 4 is a view in longitudinal central section, the adjusting stem being partly broken out to save space. Fig. 5 is a detail view of the float valve. Fig. 6 is 70 a detail view of the sleeve-like air valve. Fig. 7 is a fragmentary view on an enlarged scale, partly in section and partly in elevation, of the improved valve tube and showing its disposition with respect to the carbureting sleeve.

The main body *a* of the casing is generally cylindrical and forms or incloses the mixing chamber *a'*. It has upon its upper side, near one end, a dome *a*² within which is formed the passage *a*³ through which the mixture passes from the carbureter on its way to the engine, the dome being provided with a flange *a*⁴ by which the carbureter may be secured in position. The ends 80 of the cylindrical portion *a'* of the casing are closed by caps *a*⁵ and *a*⁶, the latter forming also a guide for the adjusting stem hereinafter referred to. On its under side the main body *a* is formed with a circular flange *a*⁷ to receive the upper end of the float-tank or chamber and with an inner flange *a*⁸ to receive a carbureting sleeve hereinafter referred to, an opening *a*⁹ being provided within the flange *a*⁸ through which the 95 primary mixture passes to the mixing chamber *a'*.

The float-tank or chamber *b* fits against the flange *a*⁷ and is secured in place as will be described. It is formed at one side with 100 a communicating float-valve chamber *b'*, in which is mounted a float-valve *c* which comprises a sleeve *c*' mounted to slide vertically in a gland *c*² and provided with a circumferential groove *c*³, and a valve stem *c*⁴ 105 which is threaded in the sleeve *c*', and is provided with a jam-nut *c*⁵ and with a suitable head *c*⁶ by which the inflow of gasoline from a suitable supply through an aperture *c*⁷ is controlled. The float *d* is annular, for 110

a reason which will appear, and is hung, through ears d' , from a forked lever d^2 which is pivoted as at d^3 , the other end d^4 of the lever being also forked and engaging the circumferential groove c^3 of the sleeve c .
5 The float and valve act in the usual manner to maintain the level of the gasoline in the tank b at a predetermined height.

In the flange a^8 is threaded a primary mixing valve sleeve e . The tank b has in its bottom an opening b^2 which receives the sleeve e snugly, the bottom of the tank bearing against a flange e' on the sleeve, while a nut e^2 is threaded on the sleeve to press the 10 bottom of the tank tightly against the flange e' . Below the nut e^2 the sleeve is provided with openings e^3 for the admission of the bottom or primary air which first forms a mixture with the gasoline vapor. The 15 sleeve e is also provided interiorly with the valve tube e^8 , the interior of which communicates with the float-chamber b through perforated lugs e^4 . In the upper end of the valve tube e are formed two openings 20 e^5 and e^6 , the former having its mouth at a slightly higher level than the latter. In the lower end of the tube e^8 is threaded the set needle valve e^7 , which may be manipulated from the outside for the purpose of 25 regulating the flow of gasoline through the opening e^5 . With the other opening e^6 cooperates the needle valve hereinafter described.

The cylindrical mixing chamber is formed 30 in its side with a triangular, variable air inlet a^{10} which is controlled by a sleeve-like air valve f which is mounted to slide with a free fit in the chamber, is closed at one end, as at f' , has a long slotted opening f^2 in 35 its underside to register with and leave unobstructed in any position the opening a^9 in the bottom of the casing, has in its upper side an opening f^3 to register with and, it may be, also to regulate the passage a^3 , the 40 opening f^3 being extended rearwardly or to the right hand in Fig. 4, as at f^4 , for a purpose to be explained, and, it may be, has in its side a narrow slot f^6 which is entered by a guide pin f^6 in the side of the casing a 45 to prevent rotation of the sleeve. At its forward or right hand end the sleeve is provided with a transverse arm f^7 into which is threaded the operating stem g which is guided in the head a^6 and may be 50 connected by any suitable means to the throttle lever. The stem is threaded as at g' and receives an adjusting stop g^2 through which the inward movement of the stem and the opening movement of the sleeve may 55 be adjusted. A screw g^3 , threaded in the cap a^6 , serves to limit the outward movement of the stem and the closing movement of the sleeve valve by contact with the arm f^7 .
60

65 A butterfly valve h is mounted in the pas-

sage a^3 on a suitable stem h' and to the latter is secured adjustably an arm h^2 . The end of the arm, which is slipped upon a stem h' , is split and provided with a clamping screw h^3 so that the arm can be secured 70 upon the valve in any desired position of adjustment with respect to the valve h . A link i , pivotally engaged at one end with an arm h^2 , is pivotally engaged at its other end with an arm k which is threaded on 75 the stem g , a jam-nut k' being provided for the purpose of securing it in position. The arm k , when disconnected from the link i , may be moved to adjusted position on the stem, to provide an additional means of adjustment between the sleeve valve f and the butterfly valve h , besides the means of adjustment provided by the adjustable arm h^2 .
80

The needle valve, which co-operates with the opening e^6 of the valve e^8 , comprises a 85 needle valve stem l which is threaded in a sleeve l' and is provided with a jam-nut l^2 and with a suitable head l^3 . The sleeve l' is itself threaded in a boss a^{11} of the casting a and is provided at its lower end, 90 within the sleeve f , with an arm l^4 . The arm is split at the end which engages the sleeve l' and is provided with a clamping screw l^5 so that the arm can be secured in adjusted position upon the sleeve l' . The 95 arm l^4 is also slotted as at l^6 to engage a pin f^8 which is carried by a bracket f^9 which projects inwardly from the wall of the sleeve f .

The operation of the carburetor will now 100 be understood readily.

A suitable supply of gasoline being provided, the level of the gasoline in the float-tank or reservoir b is maintained at a predetermined height by the operation of the float and float-valve in the usual manner. From the tank b the gasoline passes to the gasoline tube e and flows out through the openings e^5 and e^6 at the top. The opening e^5 is manually controlled by the set valve 110 e^7 , so that, if desired, a constant flow may be maintained regardless of the condition of the aperture e^6 , through which the principal flow takes place during the operation of the engine and in which the flow is regulated, at the will of the operator, in accordance with the requirements of the work being done by the engine and in proper proportion to the inflow of air through the air inlet a^{10} . The initial air, which forms the 115 first mixture with the gasoline vapor, enters through the openings e^3 in the sleeve e and takes up the gasoline vapor from the end of the tube e^8 , the tube e being suitably shaped interiorly to direct the air. The 120 mixture passes from the sleeve into the mixing chamber a' , where additional air may or may not be supplied from the inlet a^{10} , as conditions may render desirable. With the flow of gasoline through the aper- 125 130

ture e^6 cut off altogether or reduced very much, the air inlet a^{10} is closed or nearly closed and the necessary air is supplied through the openings e^3 , but when the flow of gasolene is increased by movement of the stem g , sleeve f , sleeve nut l' and needle valve l , the air inlet a^{10} is opened wider and eventually practically all of the air is admitted through the inlet a^{10} . When the flow of gasolene is small and the quantity of air admitted is also small the suction by which the mixture is withdrawn from the carbureter should also be small, and as the flow of gasolene is increased for heavier duty the suction should also be increased in proportion. Therefore the butterfly valve h is operatively connected, through the link i , arm k and stem g , with the needle valve l and the sleeve valve f and is opened or closed in accordance with the movement thereof.

It will be seen that independent adjustments of the slide valve, the needle valve and the butterfly valve can be made to suit the requirements of the engine and that when once made the supply of the mixture to the engine, according to the conditions of operation, is under perfect control of the operator and that the supply of air, the supply of gasolene and the suction are then regulated each in proportion to the variation of the others and that the proper relation is at no time disturbed. It will also be seen that the desired regulation is effected without the use of springs or weights or parts movable by the suction of the engine so that the action of the carbureter, when once adjusted, can be depended upon absolutely under all conditions and for long continued use. Obviously, also, the butterfly valve might be disconnected from the air valve, by simply disconnecting the link i and the connection made from the arm h^2 to the engine governor so that the butterfly valve may be controlled by the governor.

It will be understood that various changes in details of construction and arrangement may be made and that some of the features of improvement are capable of use independently of others and in structures of other forms than the form shown and described herein.

I claim as my invention:—

1. In a carbureter, the combination of a mixing chamber, a gasolene nozzle supported below the same, a needle valve to co-

operate with said nozzle, an externally threaded sleeve mounted in the wall of the mixing chamber and supporting the needle valve, and a sliding air valve in said mixing chamber, said threaded sleeve having a slotted arm engaging the sliding air valve

2. In a carbureter, the combination of a mixing chamber having an opening for the admission of the primary mixture, an opening for the admission of air and an opening for communication with the engine, a gasolene nozzle, a needle valve to cooperate with said nozzle, means to regulate said needle valve, a suction controlling valve mounted in the opening which communicates with the engine, an independent sliding air valve and operative connections between said sliding valve, said regulating means and said suction controlling means, whereby all of said parts are moved together.

3. In a carbureter, the combination of a mixing chamber having an opening for the admission of the primary mixture, an opening for the admission of air, an opening for communication with the engine, a gasolene nozzle, a needle valve to cooperate with said nozzle, independently adjustable means to regulate the needle valve, a sliding air valve, an operative connection between the sliding air valve and said means, a suction controlling valve in the opening which communicates with the engine, and independently adjustable operative connections between said sliding air valve and said suction controlling valve.

4. In a carbureter, the combination of a mixing chamber having an opening for the admission of the primary mixture, an opening for the admission of air and an opening for communication with the engine, a gasolene nozzle, a needle valve to cooperate with said nozzle, an externally threaded sleeve mounted in the wall of the mixing chamber to support said valve, and a sliding air valve in said chamber slotted for the accommodation of the needle valve, said externally threaded sleeve having within the sliding air valve a slotted arm and said sliding air valve having interiorly a lug to engage said slotted arm.

This specification signed and witnessed this 26th day of April, A. D. 1912.

RICHARD W. GALLAGHER.
